BALANCED DUPLEXER

Henry J. Riblet, Belmont, Mass., assignor to Raytheon Manufacturing Company, a corporation of Delaware

Application July 30, 1948, Serial No. 41,509

19 Claims. (Cl. 178—44)

1
This invention relates to duplexers for radar systems of the type that employ a single antenna for transmitting and receiving, and more particularly to an improved balanced duplexer for such systems.

It is an object of the invention to provide a balanced duplexer which affords greater broadband characteristics than have heretofore been available.

It is another object to provide a duplexer which affords optimum decoupling between the transmitter and receiver during reception, and improved protection to the elements of the receiver input circuit during transmission.

It is another object to provide a balanced duplexer which is more compact, smaller, and less complex than known balanced duplexers employing magic tee and rat race bridges, and which is adaptable to construction in small sizes comparable with known single-tube duplexers.

The basic idea of a balanced duplexer is well known to the art. In an article by E. G. Schneider entitled "Radar," Proceedings of the I. R. E., August 1946, starting at page 551, mention is made of two specific types, one involving a rat-race type of circuit, and the other using magic tees. Such balanced duplexers are discussed in "Microwave Duplexers," by L. D. Smullin and C. G. Montgomery, McGraw-Hill Book Co., Inc., New York, 1948; pages 350 to 369, inclusive. The rat-race bridge is called a "ring-circuit magic tee" in this book. These two types of balanced duplexers are characterized mechanically by space-consuming angular waveguide or coaxial line junctions, and electrically by line sections of critical length, such as quarter wave sections, which are necessary to the proper operation thereof. The balanced duplexer of the present invention employs directional couplers in place of rat-race bridges and magic tees, with a consequent economy of space and reduction in complexity. No line section of critical length is required.

In general, balanced duplexers have certain advantages over the single-tube types, among these being the fact that they have better broadband characteristics. The present duplexer has these advantages in addition to the particular advantages that flow from its unique construction. Other and further advantages and features of the invention will become apparent from the description thereof that follows, reference being made to the accompanying drawings, wherein:

Fig. 1 is a side sectional view of an embodiment of the invention;

Fig. 2 is a fractional section along line 2—2 of Fig. 1, showing a plan view of a directional coupler;

2
Fig. 3 is a cross-section along line 3—3 of Fig. 1;

Figs. 4A and 4B are diagrams illustrating the operation of the directional couplers; and

5 Figs. 5A and 5B and 6A and 6B are vector diagrams illustrating the operation of the directional couplers.

Referring now to Figs. 1, 2 and 3, two similar rectangular waveguides 11 and 12 are directionally coupled together by a directional coupler A through a common wide wall 13. The coupler has two input ends 14 and 15, and two output ends 16 and 17. The input ends 14 and 15 are connected to the antenna and the transmitter, respectively (both not shown), of the radar system, and the output ends 16 and 17 are each connected to an electronic switch device, here is a pair of T-R tubes 18 and 19, respectively.

The T-R tube is an impedance changing device 20 which functions in a well-known manner to provide in effect a short circuit when it is fired by a voltage exceeding the firing value. The present T-R tubes 18 and 19 each provide such a short circuit across the transmission line in which it is connected when the transmitted voltage exceeds the firing value, but is effectively a matched section of the line at lower voltages. These tubes are constructed in a section of rectangular waveguide of the same kind electrically as that used for transmission line in the radar system, and are each provided with a wave-pervious gas impervious window 21 at each end and a pair of spark electrodes 22 and 23 disposed in the guide section between the windows in the region of highest voltage gradient for the fundamental or TE_{0,1} mode. One electrode 23 in each tube is formed as a hollow truncated cone and has a keep-alive electrode 27 disposed within it. The keep-alive electrode is insulated from and supported on the metal of the waveguide by a non-conductive, gas impervious support 24, which may be made of glass, and projects therethrough, terminating in an electrical connection cap 25. A keep-alive potential is applied to each cap 25 by a suitable unidirectional voltage source, such as a battery 26. As will be shown, the present invention is inherently a broad-band device. To take full advantage of the broad-band properties of the invention, it is preferred to employ a T-R tube which also is broad-band in nature, for example, the multi-gap type 1B63, which is described in the aforementioned book, Smullin and Montgomery, at page 231; and in theory at page 111. It is understood, however, that other types of T-R tubes may be used if desired.

40 A second pair of mutually similar rectangular waveguides 31 and 32 are directionally coupled together through a common wide wall 33 by a

50

second directional coupler B. Coupler B has two input ends 34 and 35 and two output ends 36 and 37. The input ends 34 and 35 of coupler B are connected to the T-R tubes 18 and 19, respectively, and the output ends thereof are connected to a non-reflective termination 38 and to the radar receiver (not shown), respectively. The non-reflective termination may conveniently be a wedge-shaped piece of hard wood, or Bakelite, coated with an electrically resistive material, such as colloidal carbon, known as "Aquadag."

It will be seen that the balanced duplexer of Fig. 1 comprises essentially two separate waveguide transmission lines, one consisting of sections 11, 18 and 31 connected between the antenna and the non-reflective termination 38, and the other consisting of sections 12, 19 and 32 connected between the transmitter and the receiver, the lines being directionally coupled together by couplers A and B at two spaced apart points or regions, and each having a set of T-R tube electrodes 22 and 23 which are effective at a point as region intermediate the coupling points or regions. The duplexer has as its input terminals the input ends 14 and 15 of coupler A, and as its output terminals the output ends 36 and 37 of coupler B.

The directional couplers A and B are preferably of any type which can be dimensioned to function as a hybrid; that is, which can be so dimensioned that power that is incident upon a terminal at one end is evenly divided and appears in equal quantities at both terminals at the other end. Such a coupler is said to have a coupling ratio of 1:1, or unity. Inasmuch as the power which is incident upon a terminal at one end of the coupler appears at the other end thereof, each directional coupler A or B may be said to be of the kind which couples in the forward direction. In addition, the couplers should preferably be electrically symmetrical; that is, a wave being coupled should encounter the same electrical conditions on either side of it. Such a coupler is a quadrature phase shift device, and its employment simplifies the construction of a broad-band balanced duplexer, as will be explained. It will be helpful in understanding the operation of the invention to understand that quadrature phase shift is characteristic of symmetrical directional couplers in general and of the couplers illustrated in particular, as will be explained below. The couplers A and B that are illustrated in Figs. 1 to 3, inclusive, are preferred for their inherently small size, natural symmetry, and ease of construction and design.

Couplers A and B each consist of a plurality of transversely directed slots 42 centered substantially along the center line of the wall 13 or 33, respectively, in which they are cut, and a plurality of longitudinally directed slots 43 disposed near the edges of the wall. The couplers are of the kind which is described in detail and claimed in copending application, Serial No. 784,277, filed November 5, 1947. It will be recognized by those skilled in the art that when the fundamental or TE_{0,1} mode of wave propagation exists in the various waveguides, the individual slots 42 and 43 of the couplers are each disposed perpendicular to the direction of current flow in the wall in which it is cut, so that each slot is disposed advantageously to be excited by this mode. The slots are preferably all made thin, so that each slot will be excited principally by that field which

gives rise to a current tending to flow across its long dimension, and no other.

The coupling ratio of each coupler is adjusted to unity, so that each coupler functions as a "hybrid," and couples substantially one-half of the power presented to it. To this end the slots of each coupler are made non-resonant to waves in the operating frequency band, so that each slot couples only a small amount of the power presented to it, and the number of slots of each coupler is then chosen to effect a coupling ratio of unity. In order that the coupling ratio shall remain reasonably constant over the operating frequency band, all the slots are maintained short with respect to the longest guide wavelength being coupled; the slot lengths should not be equal to or exceed one half the longest guide wavelength in the band. With respect to the present couplers, these features of construction are explained in detail in the aforementioned copending application, where the form of coupler in which the coupling ratio is unity is referred to as a "bridge circuit." As developed in said copending application, the spacing between slots of couplers like A and B has little or no effect on the coupling ratio, but there is an improvement in directivity when the spacing is reduced, as in the embodiment illustrated in Fig. 11 of said application. The coupling ratio is determined by the nature of the individual slots and the number of slots employed in each coupler.

Each of the directional couplers A and B is a quadrature phase-shift device; that is, the output voltages differ in phase by 90 degrees. Their quadrature nature is due mainly to their symmetry; for example, a coupler A couples two identical waveguides 11 and 12 symmetrically; that is, the same mechanical and electrical configuration is presented to waves on either side of the coupler.

Considering now one of the symmetrical directional couplers, for example, the coupler A, if the coupler were infinitely directive in the forward direction, an ideal situation which is not fully realized but is closely approached in practice, all the power incident upon either of its input ends 14 or 15 would become available at the two output ends 16 and 17 in equal amounts, because the coupler is a hybrid. The ideal situation can be synthesized for symmetrical directional couplers in general by introducing two separate sets of waves into the two input ends, as illustrated in Figs. 4A and 4B, where coupler A is considered as an example in which power is incident upon input end 14. As shown in Fig. 4A, two waves of equal intensities and symmetrical, or of like phase as seen from the common wall 13, represented by vectors 51 and 53, are assumed to be introduced into or incident upon the two input ends 14 and 15, respectively. Simultaneously, as shown in Fig. 4B, two additional waves which are antisymmetric or mutually oppositely phased as seen from the common wall 13, represented by vectors 52 and 54, are assumed to be incident upon the input ends 14 and 15, respectively. Vector 52 is in phase with vector 51, in consequence of which vector 54 is oppositely phased to vector 53. Thus, at one input end 14, a voltage exists, which is the sum of two symmetric voltages, represented by vectors 51 and 52, while the voltage at the other input end 15 is zero, being the sum of two antisymmetric vectors 53 and 54 of equal magnitude. This is the actual physical situation that exists at the input ends

of the directional coupler when power is introduced through input end 14, and the directivity is ideal, or infinite.

Consider now the condition of the four vectors 51, 52, 53 and 54 at the output ends 16 and 17 of the coupler. Assuming no reflections, which is the case for ideal performance, i. e. infinite directivity, and perfect matching, all the incident power will arrive at these output terminals in equal amounts, except for very small line attenuations affecting all the vectors equally, it being remembered that the transmission paths are similar. However, at the coupler A, where the common wall 13 is slotted and the fields in the two waveguides can interact, vectors 51 and 53 generate, in effect, a symmetrical mode of transmission in the two coupled waveguides 11 and 12, while vectors 52 and 54 generate, in effect, a different, antisymmetric mode. In general, these two coupling modes have different phase velocities in the waveguides at the coupler. It has been found that the phase velocity of the antisymmetric mode is not substantially changed from the normal waveguide phase velocity of the individual components, but that the phase velocity of the symmetric mode tends toward the lower free space velocity of electromagnetic waves. Thus, while vectors 51 and 53 maintain their initial symmetry, and vectors 52 and 54 maintain their initial antisymmetry, the phase relation between vectors of one coupling mode and those of the other coupling mode is different at the output ends 16 and 17 from the relation that exists at the input ends 14 and 15. This situation is illustrated in Figs. 5A and 5B, where vectors 51 and 53 are still symmetric and vectors 52 and 54 are still antisymmetric, but vectors 52 and 54 have been shifted clockwise, each by the same angular amount, with respect to vectors 51 and 53, respectively. The amount that the vectors of one mode are shifted with respect to the vectors of the other mode depends on the length of the coupler. The vectors 51 and 52 in the first output end 16 (Fig. 5A) have a resultant phase illustrated by vector 55, while the vectors 53 and 54 in the second output end 17 (Fig. 5B) have a resultant phase illustrated by vector 56. The phase difference between the two resultants is 90 degrees, and since the foregoing discussion is general to symmetrical directional couplers, this is true regardless of the kind of symmetrical directional coupler that is used, or the frequency of operation.

The general symmetrical directional coupler is thus seen to be a quadrature phase shift device for all frequencies and regardless of the coupling ratio; that is, at the output terminals the source or direct voltage and the coupled voltage differ in phase by, 90 degrees; or in other words, the coupler introduces a 90-degree phase shift in the coupled voltage. It is thus distinguished from the magic tee, which is characterized by a phase shift of 180 degrees or zero. Which of the output voltages, as represented by vectors 55 and 56, lags or leads the other is determined by the nature and length of the particular directional coupler employed, but in a particular coupler the sense of the phase difference is the same regardless of the direction in which power passes through the coupler, since in both directions the paths are symmetrical. In the present directional couplers, where the coupling is through a common wide wall 13 or 33, the coupled voltage 56 lags behind the source voltage 55.

Since the directional couplers that are employed in the invention are also hybrids, the power levels at the two output ends 16 and 17 are equal. In Figs. 5A and 5B, vectors 55 and 56 are not equal, illustrating a non-hybrid coupling condition. In Figs. 6A and 6B, the hybrid condition, arrived at by proper adjustment of the length of the coupler as discussed above, is illustrated. The length of the coupler is such that vectors 51 and 52, and 53 and 54, are respectively 90 degrees apart, in consequence of which the resultants 57 and 58 are equal, but still in phase quadrature. The physical significance of this is that while the quadrature phase shift character of a symmetrical directional coupler is fixed regardless of the coupling ratio, the electrical length for a symmetrical hybrid directional coupler is 90 degrees different for one coupling mode than for the other; i. e., the length is such that in each output end the voltage of one mode is 90 degrees different in phase from the voltage of the other mode. The present coupler is aptly termed a "quadrature hybrid." The foregoing discussion applies equally to directional coupler B, which is also symmetrical, so that each coupler is a quadrature hybrid.

The operation of the duplexer of Fig. 1 is as follows. When the transmitter is operated, power enters the transmitter input terminal 15, and is divided equally in directional coupler A, equal portions arriving at the T-R tubes 18 and 19, but with the voltage at tube 18 lagging that at the other tube by 90 degrees. This power fires the two T-R tubes simultaneously, and is reflected into coupler A. Power reflected from the upper T-R tube 18 divides equally at the coupler and proceeds into the input terminals 14 and 15 in equal amounts, with an additional phase lag of 90 degrees, or a total of 180 degrees, in the voltage reflected into the transmitter input terminal 15. Power reflected from the lower T-R tube 19 divides equally at the coupler and proceeds into the input terminals 14 and 15 in equal amounts, with no voltage phase change introduced into the power reflected to the transmitter terminal 15 and a voltage phase lag of 90 degrees introduced in the voltage reflected to the antenna terminal 14. Thus, the voltages of the two reflected power components in the transmitter input terminal 15 are antisymmetric, or 180 degrees out of phase with each other, while the voltages of the two reflected power components in the antenna terminal 14 are symmetric, or in the same phase, since each component has passed through the coupler A once, and has been delayed by the same amount, namely 90 degrees. Since the two power components at the two T-R tubes are equal, there is substantially complete cancellation of reflected power at the transmitter input terminal 15. The reflected power components in the antenna terminal 14 are added to each other and proceed to the antenna.

In general, the major portion of the power that leaks or escapes through the T-R tubes and arrives at the receiver during transmission is that which is generated in the tubes themselves, such as noise. Measurements made on the present balanced duplexer have indicated that there is very little component of leakage power that is related in phase to the transmitter power. In this respect, the present duplexer is comparable to other known balanced duplexers, and superior to the conventional single tube duplexers, with or without the anti T-R. Components of leakage power that are in phase with the transmitter

power can be expected to be generally proportional thereto in magnitude. No such component has been detected with the present duplexer. As a consequence, the protection afforded during transmission by the present duplexer to the crystals employed for radio frequency detection in microwave radar receiving systems is excellent.

Except for the losses due to the T-R tubes themselves and normal line losses, all the power from the transmitter proceeds to the antenna. The voltage V_0 that is introduced into the duplexer from the transmitter is divided vectorially in coupler A, each portion having the magnitude:

$$\frac{V_0}{\sqrt{2}}$$

Each portion is further divided after reflection from the T-R tubes, the ultimate portions each having the magnitude:

$$\frac{V_0}{\sqrt{2}\sqrt{2}} = \frac{V_0}{2}$$

Due to the phase consideration, as set forth above, existing in terminals 14 and 15 with respect to these ultimate portions, the voltage present in the antenna terminal 14 is

$$\frac{V_0}{2} + \frac{V_0}{2} = V_0$$

whereas the voltage present in the transmitter input terminal 15 due to reflection from the T-R tubes 18 and 19 is

$$\frac{V_0}{2} - \frac{V_0}{2} = 0$$

Thus, the total voltage of the source is applied to the antenna, and hence the total power.

During reception, the power that is incident upon the antenna is brought to the antenna terminal 14, and thence to coupler A, where it is divided evenly and proceeds in equal amounts through the two T-R tubes 18 and 19, without firing the tubes. The two waveguide sections of the tubes are matched to the respective output ends 16 and 17 of coupler A and the respective input ends 34 and 35 of coupler B to which they are connected. The voltages in the T-R tubes have a phase difference of 90 degrees, with a particular sense, which in the present embodiment is such that the voltage in the lower tube 19 lags. The power from the upper tube 18 enters coupler B and is divided evenly, equal portions proceeding into the duplexer output terminals 36 and 37, with a phase difference of 90 degrees. Since coupler B is identical to coupler A, the sense of this phase difference is the same as that introduced by coupler A in operating on the antenna power. Thus the voltage in the receiver terminal 37 from the upper T-R tube 18 is delayed by 90 degrees in passing through coupler B and lags that in the closed terminal 36 from the same tube 18 by 90 degrees. Since the voltage in the lower tube 19 already lags the voltage in the upper tube 18 by 90 degrees, the two voltage components from the two T-R tubes are in the same phase in the receiver terminal 37, and are added to each other. It may be noted that each voltage component in the receiver terminal 37 passed through one coupler in arriving there from the antenna. The voltage from the lower tube 19 that reaches the closed terminal 36 through coupler B must pass through two couplers in arriving there from the antenna so that it is delayed by a total of twice 90 degrees with respect to the voltage that arrives in that terminal

via the upper tube 18 so that, being of equal magnitude, these two voltages cancel each other. The non-reflective termination serves to absorb and prevent the reflection of any small uncancelled voltage component that may be present in the closed terminal 36. In the same manner as was explained above with relation to transmitted power, all the power received at the antenna is furnished to the receiver, except for general system losses, which are small and not due to the invention.

The value of employing quadrature phase shift directional couplers is now seen to be that with them it is only necessary to place both T-R tubes 18 and 19 the same effective distance from each coupler A or B to attain a broad-band balanced duplexer; that is, the effective short circuit of each tube is the same distance from coupler A for each tube, and the same distance from coupler B for each tube. The distance from A is not necessarily the same as the distance from B, however. The proper dimensions are arrived at simply by constructing a symmetrical system, as shown in Fig. 1. Then, automatically, substantially all the transmitted power introduced at terminal 15 goes to the antenna via terminal 14, and substantially all the received power at terminal 14 goes to the receiver terminal 37. No quarter wave or other phase adjusting section is necessary with this construction to render the device frequency critical.

In the embodiment of the invention described above, the component parts are all available with broad-band characteristics. The couplers A and B can be made broad-band as taught in the aforementioned copending application. The T-R tubes are available with broad-band characteristics, for example, the type 1B63. Data taken from a model designed for operation at the frequency 9090 mc./sec., employing broad-band components, is as follows:

I. The low level data, namely the performance during reception, with power being fed from the antenna terminal 14 to the receiver terminal 37, showing: the input voltage standing wave ratio (VSWR) in terminal 14; the insertion loss in decibels (db) from terminal 14 to terminal 37, and the overall directivity or level of antenna power at the transmitter terminal 15 compared to the level of power at the receiver terminal 37, expressed in decibels down (-db):

Frequency Mc./Sec.	Input VSWR	Loss db	Directivity -db
9,660	1.15	1.6	9.0
9,375	1.14	0.75	22.6
9,090	1.08	0.70	25.5
8,825	1.18	0.75	16.25
8,575	1.17	0.75	17.6

The low level loss due to the keep-alive alone was found to be negligible.

II. The high level data, namely the performance during transmission, taken with a type 2J51 magnetron as transmitter, pulse operated at about 25 kw., 1000 pulses per second, and 1 microsecond pulse width:

VSWR (in terminal 15) = 1.1

Insertion loss (from terminal 15 to terminal 37) = 2.4 db

Leakage power = 19 microwatts

Recovery time = a property of the T-R tubes

The insertion loss of 2.4 db is the loss customarily encountered with type 1B63 tubes. It is a constant quantity for the tube, and hence the loss in db of the duplexer decreases with increasing power from the magnetron.

III. The magnetron decoupling was found to be superior to that of conventional duplexers over the band from 8575 to 9660 mc./sec. If an adjustable plunger is put in the arm of the transmitter terminal 15, and a signal is fed from the antenna terminal 14 to the receiver terminal 37, the effect of variations in the position of the plunger arm will give an indication of magnetron, or transmitter decoupling. In a conventional or single tube duplexer, the plunger will have no effect at the design frequency, but at the edges of the band (8575 to 9660 mc./sec.), sharp resonances as high as 5 db have been observed. These resonances are observed at variations in the power present in the receiver terminal 37. Tests made on the present balanced duplexer show no effect at the design wavelength, and a maximum variation of 1.55 db at the worst edge of the band. This was a gradual variation, and not a sharp change. The data is

Frequency	Variation in Terminal 37 (db)
9,660	1.55
9,375	0.10
9,030	0.09
8,825	0.20
8,575	0.50

Since there is no anti T-R, the usual anti T-R resonance effects exhibited in the conventional duplexer at frequencies away from the design frequency did not occur.

Many modifications of the illustrated embodiment of the invention will occur to those skilled in the art without departing from the spirit and scope thereof. The features of extreme compactness and small size can be attained with practically any form of directional coupler which couples two substantially parallel line sections through a common wall, so that power entering one of the lines at one end emerges from both lines at the other end. However, other forms may be employed, as those skilled in the art will readily recognize; for example, coupling need not necessarily be effected through a common wall. It is accordingly intended that the claims that follow shall not be limited by the details of the illustrated embodiment, but only by the prior art.

In the claims that follow, the term "directional coupler" shall be understood to mean a device consisting of a first, or main, electromagnetic wave transmission line and a second, or auxiliary, electromagnetic wave transmission line, each line having two ends, or terminals, the lines being coupled together at a point, or points, intermediate the ends of each, which, when there exist waves traveling in both directions in the main line, delivers to one end of the auxiliary line a voltage which is largely a function of the amplitude of the wave going in one preferred direction in the main line, and relatively independent of the wave going in the opposite direction in the main line.

I claim:

1. A duplexer adapted to be used with ultrahigh frequency electromagnetic wave energy comprising: first and second electromagnetic

wave transmission line sections, each section having a first end and a second end; means directionally coupling said sections together at each of two spaced-apart regions, each of said coupling

means being arranged to couple energy arriving thereat directly from an end of one of said line sections into the other of said line sections propagating substantially exclusively toward the other of said coupling means; and means in each line intermediate said two regions for causing an abrupt change in the impedance characteristic of the line in response to the presence in said line of a voltage exceeding a certain magnitude.

2. A duplexer adapted to be used with ultrahigh frequency electromagnetic wave energy comprising: first and second electromagnetic wave transmission line sections, each section having a first end and a second end; first and second directional couplers arranged directionally to couple said sections together at each of two spaced-apart regions, each of said couplers being arranged to couple energy arriving thereat directly from an end of one of said line sections into the other of said line sections propagating substantially exclusively toward the other of said couplers; and means in each line intermediate said two regions for causing an abrupt change in the impedance characteristic of the line in response to the presence in said line of a voltage exceeding a certain magnitude.

3. A duplexer adapted to be used with ultrahigh frequency electromagnetic wave energy comprising: first and second electromagnetic wave transmission line sections, each section having a first end and a second end; first and second electrically similar directional couplers arranged directionally to couple said sections together at each of two spaced-apart regions, each of said couplers being arranged to couple energy arriving thereat directly from an end of one of said line sections into the other of said line sections propagating substantially exclusively toward the other of said couplers; and means in each line intermediate said two regions for causing an abrupt change in the impedance characteristic of the line in response to the presence in said line of a voltage exceeding a certain magnitude.

4. A duplexer adapted to be used with ultrahigh frequency electromagnetic wave energy comprising: first and second electromagnetic wave transmission line sections, each section having a first end and a second end; first and second quadrature phase change directional couplers arranged directionally to couple said sections together at each of two spaced-apart regions, each of said couplers being arranged to couple energy arriving thereat directly from an end of one of said line sections into the other of said line sections propagating substantially exclusively toward the other of said couplers; and means in each line intermediate said two regions for causing an abrupt change in the impedance characteristic of the line in response to the presence in said line of a voltage exceeding a certain magnitude.

5. A duplexer adapted to be used with ultrahigh frequency electromagnetic wave energy comprising: first and second electromagnetic wave transmission line sections, each section having a first end and a second end; first and second quadrature phase change directional couplers arranged directionally to couple said sections together at each of two spaced-apart regions, each of said couplers being arranged to couple energy arriving thereat directly from an end of one of said line sections into the other of said line sec-

tions propagating substantially exclusively toward the other of said couplers; and means in each line intermediate said two regions for causing an abrupt change in the impedance characteristic of the line in response to the presence in said line of a voltage exceeding a certain magnitude, said impedance changing means both being substantially equidistant from the first of said coupling regions, and substantially equidistant from the second of said coupling regions.

6. A duplexer adapted to be used with ultra-high frequency electromagnetic wave energy comprising: first and second electromagnetic wave transmission line sections, each section having a first end and a second end; first and second hybrid directional couplers arranged directionally to couple said sections together at each of two spaced-apart regions, each of said couplers being arranged to couple energy arriving thereat directly from an end of one of said line sections into the other of said line sections propagating substantially exclusively toward the other of said couplers; and means in each line intermediate said two regions for causing an abrupt change in the impedance characteristic of the line in response to the presence in said line of a voltage exceeding a certain magnitude.

7. A duplexer adapted to be used with ultra-high frequency electromagnetic wave energy comprising: first and second electromagnetic wave transmission line sections, each section having a first end and a second end; first and second symmetrical hybrid directional couplers arranged directionally to couple said sections together at each of two spaced-apart regions, each of said couplers being arranged to couple energy arriving thereat directly from an end of one of said line sections into the other of said line sections propagating substantially exclusively toward the other of said couplers; and means in each line intermediate said two regions for causing an abrupt change in the impedance characteristic of the line in response to the presence in said line of a voltage exceeding a certain magnitude.

8. A duplexer adapted to be used with ultra-high frequency electromagnetic wave energy comprising: first and second electrically similar electromagnetic wave transmission line sections, each section having a first end and a second end; means directionally coupling said sections together at each of two spaced-apart regions, each of said coupling means being arranged to couple energy arriving thereat directly from an end of one of said line sections into the other of said line sections propagating substantially exclusively toward the other of said coupling means; and means in each line intermediate said two regions for causing an abrupt change in the impedance characteristic of the line in response to the presence in said line of a voltage exceeding a certain magnitude.

9. A duplexer adapted to be used with ultra-high frequency electromagnetic wave energy comprising: first and second electrically similar electromagnetic wave transmission line sections, each section having a first end and a second end; means directionally coupling said sections together at each of two spaced-apart regions, said means being electrically symmetrical, each of said coupling means being arranged to couple energy arriving thereat directly from an end of one of said line sections into the other of said line sections propagating substantially exclusively toward the other of said coupling means; and means in each line intermediate said two regions

for causing an abrupt change in the impedance characteristic of the line in response to the presence in said line of a voltage exceeding a certain magnitude.

10. A duplexer adapted to be used with ultra-high frequency electromagnetic wave energy comprising: first and second electrically similar electromagnetic wave transmission line sections, each section having a first end and a second end; means directionally coupling said sections together at each of two spaced-apart regions, said means being electrically symmetrical, each of said coupling means being arranged to couple energy arriving thereat directly from an end of one of said line sections into the other of said line sections propagating substantially exclusively toward the other of said coupling means; and means in each line intermediate said two regions for causing an abrupt change in the impedance characteristic of the line in response to the presence in said line of a voltage exceeding a certain magnitude, said impedance changing means both being substantially equidistant from the first of said coupling regions, and substantially equidistant from the second of said coupling regions.

11. A duplexer adapted to be used with ultra-high frequency electromagnetic wave energy comprising: first and second electrically similar electromagnetic wave transmission line sections, each section having a first end and a second end; electrically similar directional coupler means directionally coupling said sections together at each of two spaced-apart regions, each of said coupling means being arranged to couple energy arriving thereat directly from an end of one of said line sections into the other of said line sections propagating substantially exclusively toward the other of said coupling means; and means in each line intermediate said two regions for causing an abrupt change in the impedance characteristic of the line in response to the presence in said line of a voltage exceeding a certain magnitude.

12. A duplexer adapted to be used with ultra-high frequency electromagnetic wave energy comprising: first and second electromagnetic wave transmission line sections, each section having a first end and a second end; means directionally coupling said sections together at each of two spaced-apart regions, each of said coupling means being arranged to couple energy arriving thereat directly from an end of one of said line sections into the other of said line sections propagating substantially exclusively toward the other of said coupling means; and a discharge device connected across each section at a third region intermediate said two regions for providing substantially a short circuit across each line at said third region in response to the presence in said line of a voltage exceeding a predetermined magnitude.

13. A duplexer adapted to be used with ultra-high frequency electromagnetic wave energy comprising: first and second electromagnetic wave rectangular waveguide sections, each section having a first end and a second end, said sections sharing a common wall in two separate regions spaced apart along the waveguide; means in each of said regions for directionally coupling said sections together at each region through the common wall, each of said coupling means being arranged to couple energy arriving thereat directly from an end of one of said line sections into the other of said line sections propagating

substantially exclusively toward the other of said coupling means; and means in each section intermediate said regions for causing an abrupt change in the impedance characteristic of the section in response to the presence in said section of a voltage exceeding a certain magnitude.

14. A duplexer adapted to be used with ultra-high frequency electromagnetic wave energy comprising: first and second electromagnetic wave rectangular waveguide sections, each section having a first end and a second end, said sections sharing a common wall in two separate regions spaced apart along the waveguides; quadrature phase shift directional coupler means in each of said regions for directionally coupling said sections together at each region through the common wall, each of said coupling means being arranged to couple energy arriving thereat directly from an end of one of said line sections into the other of said line sections propagating substantially exclusively toward the other of said coupling means; and means in each section intermediate said regions for causing an abrupt change in the impedance characteristic of the section in response to the presence in said section of a voltage exceeding a certain magnitude.

15. A duplexer adapted to be used with ultra-high frequency electromagnetic wave energy comprising: first and second electromagnetic wave rectangular waveguide sections, each section having a first end and a second end, said sections sharing a common wall in two separate regions spaced apart along the waveguides; quadrature phase shift directional coupler means in each of said regions for directionally coupling said sections together at each region through the common wall, each of said coupling means being arranged to couple energy arriving thereat directly from an end of one of said line sections into the other of said line sections propagating substantially exclusively toward the other of said coupling means; and means in each section intermediate said regions for causing an abrupt change in the impedance characteristic of the section in response to the presence in said section of a voltage exceeding a certain magnitude, said impedance changing means both being equidistant from the first of said regions, and equidistant from the second of said regions.

16. A duplexer adapted to be used with ultra-high frequency electromagnetic wave energy comprising: first and second electromagnetic wave rectangular waveguide sections, each section having a first end and a second end, said sections sharing a common wall in two separate regions spaced apart along the waveguides; hybrid directional coupler means in each of said regions for directionally coupling said sections together at each region through the common wall, each of said coupling means being arranged to couple energy arriving thereat directly from an end of one of said line sections into the other of said line sections propagating substantially exclusively toward the other of said coupling means; and means in each section intermediate said regions for causing an abrupt change in the impedance characteristic of the section in response to the presence in said section of a voltage exceeding a certain magnitude.

17. A duplexer adapted to be used with ultra-

high frequency electromagnetic wave energy comprising: first and second electromagnetic wave rectangular waveguide sections, each section having a first end and a second end, said sections sharing a common wall in two separate regions spaced apart along the waveguides; a directional coupler consisting of slots in the common wall in each of said regions, each of said couplers being arranged to couple energy arriving thereat directly from an end of one of said line sections into the other of said line sections propagating substantially exclusively toward the other of said couplers; and means in each section intermediate said regions for causing an abrupt change in the impedance characteristic of the section in response to the presence in said section of a voltage exceeding a certain magnitude.

18. A duplexer adapted to be used with ultra-high frequency electromagnetic wave energy comprising: first and second electromagnetic wave rectangular waveguide sections, each section having a first end and a second end, said sections sharing a common similar wall in two separate regions spaced apart along the waveguides; a directional coupler consisting of slots in the common wall in each of said regions, each of said couplers being arranged to couple energy arriving thereat directly from an end of one of said line sections into the other of said line sections propagating substantially exclusively toward the other of said couplers; and means in each section intermediate said regions for causing an abrupt change in the impedance characteristic of the section in response to the presence in said section of a voltage exceeding a certain magnitude.

19. A duplexer adapted to be used with ultra-high frequency electromagnetic wave energy comprising: first and second sections of similar electromagnetic wave waveguide, each section having a first end and a second end, said sections sharing a common similar wall in two separate regions spaced apart along the waveguides; a directional coupler consisting of slots in the common wall in each of said regions, each of said couplers being arranged to couple energy arriving thereat directly from an end of one of said line sections into the other of said line sections propagating substantially exclusively toward the other of said couplers; and means in each section intermediate said regions for causing an abrupt change in the impedance characteristic of the section in response to the presence in said section of a voltage exceeding a certain magnitude, said impedance changing means both being equidistant from the first of said regions, and equidistant from the second of said regions.

HENRY J. RIBLET.
